COMBINED SPRING AND SNUBBER FOR
RAILWAY CAR TRUCKS

George E. Dath, Mokena, Ill., assignor to W. H. Miner, Inc., Chicago, Ill., a corporation of Delaware

Application November 24, 1948, Serial No. 61,818

7 Claims. (Cl. 105—197)

1

This invention relates to improvements in snubbers for railway car trucks comprising bolster supporting spring means having frictional engagement with the truck side frame.

The main object of this invention is to provide supporting spring means for railway car trucks wherein the spring means has projecting tangs which embrace a portion of the side frame of the truck to frictionally snub the action of the usual truck spring cluster.

A more specific object of the invention is to provide spring means of the character set forth in the preceding paragraph which is in the form of a helically coiled spring member having the tangs at the top and bottom ends thereof embracing the bolster guides of the truck side frame at opposite sides and held in frictional contact with the same by the action of the spring which is under torsional tension.

Other objects of the invention will more clearly appear from the description and claims herein-after following.

In the accompanying drawings forming a part of this specification, Figure 1 is a transverse, horizontal sectional view through a portion of the side frame member of a railway car truck, illustrating my improvements in connection therewith, the section being taken on the line 1—1 of Figure 2. Figure 2 is a front elevational view of Figure 1. Figure 3 is a front elevational view, on an enlarged scale, of the combined spring and snubber shown at the right hand side of Figure 1. Figure 4 is a side elevational view of Figure 3, looking from right to left in said Figure 3. Figure 5 is a top plan view of Figure 4, showing the condition of the combined spring and snubber before being assembled with the spring cluster and side frame of the railway car truck. Figure 6 is a horizontal sectional view through the right hand truck bolster guide of the truck side frame, shown in Figure 2, illustrating in dotted lines the combined spring and snubber in its applied condition.

In said drawings, 10 indicates one of the side frame members of a railway car truck. The side frame 10, as shown, is in the form of a casting and has top and bottom members 11 and 12 connected by vertically disposed sections 13—13. As will be understood by those skilled in this art, the truck includes two side frame members 10—10, a truck bolster 14, and truck springs 15—15 at opposite ends of the bolster. The springs 15—15 are supported on the bottom members 12—12 of the side frames 10—10, and the opposite ends of the bolster 14 are guided between the sections

2

13—13 and 13—13 of the truck side frames. The sections 13—13 thus provide guide columns at opposite sides of the bolster on which the latter has vertical sliding movement. The usual top and bottom spring follower plates 16—16 are disposed at the top and bottom of each spring cluster, the same respectively abutting the bolster 14 and the bottom member 12 of the corresponding side frame. The springs 15—15 yieldingly support the bolster 14, which, in turn, supports the car body by means of the usual body bolster, not shown.

My improved combined spring and snubber, which is indicated by 17, is combined with the 15 spring cluster of the railway car truck. As shown in Figures 1 and 2, two such combined spring and snubber units 17—17 are preferably employed in connection with each cluster of truck springs 15, the same being substituted for the usual coil springs employed at the right and left hand ends of the cluster, centrally of the side frame.

My improved combined spring and snubber, as shown in the drawings, comprises broadly a coiled helical spring A having extended tangs B and C 25 at its top and bottom ends, embracing the guide column 13 at the corresponding side of the side frame at opposite sides, and a friction shoe D carried by the top tang B and cooperating with the guide column.

In carrying out my invention, the two column members 13—13 of each side frame, by which the bolster 14 is guided, are preferably provided with depressed guideways on corresponding sides thereof, as indicated by 18—18, in which the friction blocks are accommodated for sliding movement.

The spring A of the combined spring and snubber unit 17 is in the form of a helical coil interposed between the follower plates 16—16 of the 40 spring cluster of the railway car truck. The spring A has the tangs B and C at the top and bottom ends thereof elongated to embrace the corresponding guide column 13 of the side frame 10 at the opposite sides, the lower tang C bearing 45 on the outer side of said column.

The friction shoe D is in the form of a flat block secured to the extended portion of the top tang B of the spring. The shoe D is provided with a seat 19 in the form of a transverse, horizontal groove on its outer side, accommodating the extended portion of the tang B, and within which the tang is welded, as indicated at 20. The block or shoe D is slidable in the guideway 18 of the column 13 and has a flat friction surface 21 on its 50 inner side, which has sliding frictional engage-

ment with the corresponding side of the column 13.

In its applied condition, the spring A is under torsional tension, thus pressing the lower tang C and the friction shoe D into tight frictional contact with the bolster column 13.

As shown in Figure 5, the spring A, as manufactured, is coiled so that the tangs thereof lie in outwardly converging, vertical planes, whereby, in the normal condition of the spring, before application to the truck, the lateral distance between the inner side of the friction shoe D and the inner side of the bottom tang C is less than the transverse thickness of the corresponding column 13 of the truck side frame. It will thus be evident that the tangs B and C of the spring A are spread apart when applied to the column 13, thus slightly unwinding the spring and placing the same under torsional tension to press the tang C and the shoe D against the column 13.

The operation of the improved combined spring and snubber is as follows: Upon the spring cluster of a railway car truck being compressed between the top and bottom spring plates of the cluster by displacement of the bolster 14 toward the bottom member 12 of the truck side frame, my combined spring and snubber, which is interposed between the follower plates, is compressed therewith. As the coil spring A of each unit is compressed, the upper tang B is forced downwardly toward the bottom tang C, sliding the friction shoe D downwardly on the column 13 to provide the desired frictional resistance to snub the action of the truck springs. As the spring follower plates 16-16 are separated vertically during recoil of the truck springs and during recoil of the spring A, the friction shoe D of the top tang B of the spring moves upwardly on the column 13, thus snubbing the recoil action of the spring.

I claim:

1. In a combined spring and snubber for a railway car truck including a vertical guide column for the truck bolster, the combination with a vertically disposed, helically coiled bolster supporting spring member adjacent said column, said spring being under torsional tension; of top and bottom tangs on said spring member projecting laterally outwardly therefrom and embracing said guide column at opposite sides, said top tang having means rigid therewith in frictional sliding engagement with the vertical guide column.

2. In a combined spring and snubber for a railway car truck including a vertical guide column for the truck bolster, said column having lengthwise extending surfaces at opposite sides thereof, the combination with a vertically disposed, helically coiled spring under torsional tension supporting said bolster, said spring being adjacent said column; of a friction shoe slideable on the surface at one side of said guide column; and tangs at the opposite ends of said spring respectively in lateral bearing engagement with the opposite side of said guide column and said shoe to press the latter against said column.

3. In a combined spring and snubber for a railway car truck including a vertical guide column for the truck bolster, the combination with a vertically disposed, helically coiled spring supporting said bolster, said spring being arranged

adjacent said column; of extended top and bottom tangs on said spring embracing the guide column at opposite sides, said tangs being spread apart to accommodate said column, thereby placing said spring under winding tension to press the tangs against said column, one of said tangs having means rigid therewith in frictional sliding engagement with said column.

4. In a combined spring and snubber for a railway car truck including a vertical guide column for the truck bolster, the combination with a helically coiled spring supporting said bolster, said spring being disposed in vertical position adjacent said column; of a friction shoe vertically slideable on said guide column; and tangs at the top and bottom ends of said spring, said bottom tang bearing on one side of said column, and said top tang carrying the shoe and pressing the same against the opposite side of said column.

5. In a combined spring and snubber for a railway car truck including the usual truck bolster and truck springs, the combination with a friction column on said truck having a vertically extending friction surface on one side thereof; of a helically coiled vertically disposed spring adjacent said column, said spring supporting the truck bolster, said spring having laterally extended tangs at the top and bottom thereof; and a friction element movable with said top tang and engaging the friction surface of said column, said tang pressing the element against said column, said spring having the bottom tang thereof bearing on the side of said column opposite to the friction surface side thereof.

6. In a combined spring and snubber for a railway car truck having a side frame member provided with the usual bolster guide column, the combination with a coiled spring adapted to be interposed between the truck bolster and a fixed support on said side frame, said spring having laterally extended top and bottom tangs extending into embracing relation with the guide column of the side frame of the truck at opposite sides of said column, said bottom tang bearing on one side of said column; of a friction shoe bearing on the opposite side of said column, said shoe being fixedly secured to the inner side of said top tang and being pressed against said last named side of the column by said spring.

7. In a combined spring and snubber for a railway car truck, the combination with a friction column member on said truck; of a vertically disposed coil spring adjacent said column member, said spring being adapted to be substituted for one of the coils of the usual spring cluster of the truck, said spring having outwardly extended top and bottom tangs, one of said tangs having means integral therewith presenting a vertically disposed friction surface, said spring, as manufactured and before application to said truck, having said tangs laterally converging, said tangs embracing said column member at opposite sides and being forcibly spread apart to accommodate said column member therebetween, thus unwinding the spring to place the same under tension to forcibly press the tangs toward each other and said friction surface against said column member.

GEORGE E. DATH.
